UNITED STATES PATENT OFFICE.

VERONICA CONSTANCE HUSSEY, OF NASHVILLE, TENNESSEE.

DESIGN FOR A TOY ANIMAL.

Application filed July 15, 1922. Serial No. 3,094. Term of patent 8½ years.

To all whom it may concern:

Be it known that I, VERONICA CONSTANCE HUSSEY, a citizen of the United States, residing at 1901 Boscobel Street, Nashville, Tennessee, have invented a new, original, and ornamental Design for Toy Animals, of which the following is a specification, reference being had to the accompanying drawing, forming part thereof.

The figure is a perspective view of a toy animal showing my new design.

I claim:

The ornamental design for a toy animal as shown.

In testimony whereof I hereunto affix my signature.

VERONICA CONSTANCE HUSSEY.
